UNITED STATES PATENT OFFICE.

LEON MAYER, OF CHICAGO, ILLINOIS.

DESIGN FOR A BILL FOLD OR SIMILAR ARTICLE.

Application filed October 20, 1926. Serial No. 19,437. Term of patent 3½ years.

To all whom it may concern:

Be it known that I, LEON MAYER, a citizen of the United States, residing at Chicago, in the county of Cook and State of Illinois, have invented a new, original, and ornamental Design for a Bill Fold or Similar Article, of which the following is a specification, reference being had to the accompanying drawing, forming part thereof.

The figure is a perspective view of a bill fold or similar article showing my improved design.

I claim:

The ornamental design for a bill fold or similar article, as shown.

LEON MAYER.
